CLAIM

I claim the ornamental design for the drum stick holder, as shown and described.

DESCRIPTION

FIG. 1 is a perspective view of the design subject;

FIG. 2 is a left side elevational view thereof;

FIG. 3 is a right side elevational view thereof;

FIG. 4 is a top planar view thereof; and,

FIG. 5 is a bottom planar view thereof.

The broken line showing of a partial pole is included for the purpose of illustrating environment and forms no part of the claimed design.
